By

Inventor:
Joseph Banneryer
J. Banneryer

UNITED STATES PATENT OFFICE.

JOSEPH BANNEYER, OF CHICAGO, ILLINOIS.

SIGN.

Application filed May 9, 1922. Serial No. 559,582.

To all whom it may concern:

Be it known that I, JOSEPH BANNEYER, a citizen of the United States, residing in Chicago, Cook County, State of Illinois, have invented certain new and useful Improvements in Signs, of which the following, taken in connection with the drawings, is a description.

My invention has for its object the production of an improved sign designed to be used by various places of business wherein certain advertising matter is displayed which is designed to attract the attention of the public during the day, and at night to have means connected therewith for deflecting a light upon the sign from any angle thereto.

It is an object of my invention to provide a construction of this kind which is built up of a plurality of sections, having means for joining said sections together to form a complete sign frame of any size desired, and one which can be formed of a variety of designs to suit different purposes.

It is a further object of my invention to provide a sign of the class described which in its construction is provided with conduits through which electric wires may be passed to different points of connection.

It is also an object of my invention to provide a sign which shall be artistic in appearance, strong and durable and capable of a variety of advantages in form and construction in the assembly of the parts.

In the accompanying drawings I have illustrated what I now consider the preferred form of the essential features of my invention and in these drawings:—

Figure 1 is a front elevation of the complete sign,

Figure 2 is a sectional view taken on line 2—2 of Figure 1,

Figure 3 is a sectional view taken on line 3—3 of Figure 1,

Figure 4 is a detail taken on line 4—4 of Figure 1,

Figure 5 is a sectional detail taken on line 5—5 of Figure 1,

Figure 6 is a detailed elevation of one of the lighting fixtures secured to the frame,

Figure 7 is a sectional detail of the frame and a side view of the lighting mechanism at the top of the sign taken on line 7—7 of Figure 1,

Figure 8 is a sectional detail taken on line 8—8 of Figure 6,

Figure 9 is a sectional detail of a modified form of construction and—

Figure 10 is a detail taken on line 10—10 of Fig. 1.

Referring to the drawings in Figure 1, I have illustrated the parts assembled in a sign ready for use, the outer frame being composed of elongated tubular members or pipes A which may be of any size suitable for the sign desired. I contemplate also constructing these frame members which may be angular in cross section if desired, my drawing being simply illustrative of a hollow frame member.

Different lengths of pipe may be coupled together by a T-coupling A' which receives the ends of the pipe or tubular members A. A sheet metal sign plate B is provided of suitable length and width to be positioned within the frame formed by the pipe A, but out of contact therewith. The edges of this plate are rolled to form a tubular edge or bead a, which extends around the plate as shown in Fig. 1.

Extending transversely of the plate B are reinforcing strips B', which may be positioned wherever found desirable for the purpose of strengthening the plate or for dividing the plate into different sign sections as shown.

Means for securing these reinforcing strips are provided at each end thereof and consist of metal attaching members b which are shaped to conform to the outline of the pipe frame A and the bead a on the edge of the sign plate. These attaching members are placed upon each side of the tubular members A and the sign plate B and are secured together as at a' by bolts, rivets or the like which extend through the ends of both members and are fixedly secured in place.

The inner plate a' it will be observed extends through the reinforcing strip B' and through the plate B. By this means the

reinforcing strips may be placed wherever desired or removed and replaced as needed.

The attaching members are arranged in various styles to secure different forms of construction together where it is desired to construct a sign having a plurality of sign sections assembled as shown in Figure 1. In this instance an upper and lower independent sign section is attached to the top and bottom of the sign in which instance, the smaller sign frame is also formed of tubing A^2 which is attached to the main frame by means of the coupling members C, engaging the main frame A. A sign plate B^2 is provided of suitable size to fit within the frame A^2 and out of contact therewith as shown in Fig. 1, the coupling members C having engagement at the corners c thereof, with the rolled edge or bead of the sign plate B^2 .

Engaging members C—C² are provided at the upper corners of the frame A^2 also have engagement with the upper corners of the rolled edge of the plate B^2 .

25 To strengthen and secure the lower edge of the sign plate B^2 , I have provided the attaching member C³, which fits over the tubular member A of the main frame. Projecting from each end of said attaching member is an extending portion which receives the rolled edges of the plates B and B^2 , and as heretofore explained, is secured together by means of bolts c² or the like.

30 A smaller auxiliary sign may be arranged to depend from the lower edge of the main sign plate B and a tubular frame with an attaching member similar to C³ is provided as previously described. In this instance the sign plate D is provided with ornamental end pieces D², which are secured to a channel d which is constructed with the projecting member d', adapted to fit within a tubular member A, and to be fixedly secured thereto by means of screws d² or otherwise as shown in Figure 5, the central portion of said attaching member comprising an angularly bent frame member D³, which is secured to the channel d. The ends of this frame D³ receive the end of the sign plate D and is secured thereto by the bolts d⁴ passing through said frame and the plate D, shown more clearly in Figure 10.

35 Upon the lower edge of the depending auxiliary sign member is a coupling member D³, designed to be attached to the rolled edge of the sign plate D as at d³ and to fit closely around the tubular member A; both ends of said attaching member being secured through the sign plate.

40 The upper and lower auxiliary sign plates B² and D may be dispensed with where desired and the sign consist only of the elongated sign plate B with the surrounding frame members and transversely extending reinforcing strips B'.

Supported in suitable brackets e—e attached preferably to the frame A at one end of the sign plate B, is a frame member E, designed to support an electric lighting fixture, e', having a deflector E', which is adjustably mounted thereon whereby light may be directed toward and from the sign plate B at night. The bracket e is provided with an extension e², which extends into a slot cut through the wall of the frame member A and is attached thereto by means of the screw e³. When desired there may be provided at the top of the auxiliary sign plate B², an additional lighting fixture D³, having a deflector D⁴ attached thereto, as shown in Figure 1.

45 E² is a fitting constructed to be seated within an opening formed in the tubular member A, as shown in Figure 1, the wires E³ extending through the tubular member A, and to the supporting bracket E⁴ from which the lamp D³ is suspended.

50 In Figure 9, I have shown a slightly modified form of joint construction wherein the frame members may be secured together by means of bolts f, which extend through slots in the plate F, having a transversely extending strip f', on one side thereof. The oppositely facing ends of the plates F, are provided with the flanges f²—f² upon either side of which is an angle f³—f³, which flanges and angles are secured together by a bolt f⁴, passing therethrough. This affords a very convenient method of joining sections of the plate together in a modified form of frame construction.

55 I claim:

1. A sign comprising a tubular outer frame, a sign plate within said frame but out of contact therewith, a bead formed on the edges of said sign plate, attaching members secured to said plate and to the tubular members, and reinforcing strips extending across the face of the sign plate and being secured with said attaching members.

60 2. A sign comprising a tubular outer frame, a sign plate within said frame but out of contact therewith, removable attaching members fitting around said tubular frame and engaging the edges of the sign plate, reinforcing strips extending between corresponding attaching members and across the face of the sign plate, and means for securing said reinforcing strips with the attaching members.

65 3. A sign comprising a tubular outer frame, a sign plate within said frame but out of direct contact therewith, spaced apart removable attaching members fitting around said tubular members and engaging the edges of the sign plate, reinforcing strips extending across the sign plate on both sides thereof between said attaching members, brackets having engagement

through openings in the wall of the tubular member, a light deflector supported on said brackets, said deflector being adjustable toward and from the sign.

5. 4. A sign comprising a tubular outer frame, a sign plate within said frame but out of contact therewith, attaching members fitting around said tubular frame member extending on each side of the tubular mem-

bers and sign plate, reinforcing strips on 10 each side of the sign plate having engagement with said attaching members and an adjustable light deflector supported in proximity to said sign plate.

In testimony whereof I have signed this 15 specification.

JOSEPH BANNEYER.
